UNITED STATES PATENT OFFICE.

JUDSON McFELL, OF CHICAGO, ILLINOIS.

ELECTRIC SIGNAL-LIGHT FOR RAILWAY-SWITCHES.

SPECIFICATION forming part of Letters Patent No. 769,486, dated September 6, 1904.

Application filed September 28, 1903. Serial No. 174,860. (No model.)

To all whom it may concern:

Be it known that I, JUDSON McFELL, a citizen of the United States, residing at Chicago, in the county of Cook and State of Illinois, have 5 invented new and useful Improvements in Electric Signal-Lights for Railway-Switches, of which the following is a specification, reference being had to the accompanying drawings, forming a part thereof.

10 The purpose of this invention is to provide an improved means for mounting and protecting the electric circuit extending to an electric lamp employed in a signal-light for railway-switch applicable to existing forms of 15 switch-stands.

It consists in the features of construction set out in the claims.

In the drawings, Figure 1 is a partly-sectional elevation of the stand for the customary 20 switch-operating-lever mechanism with its signal-light having the lamp-support and other features of my invention. Fig. 2 is a section at the line 2 2 on Fig. 1, showing the same part upon a larger scale than Fig. 1. 25 Fig. 3 is a section at the line 3 3 on Fig. 2. Fig. 4 is a bottom plan of the lamp-housing support, broken away in section at one part to show a set-screw. Fig. 5 is a detail section at the line 5 5 on Fig. 2, showing the 30 parts on a larger scale than said Fig. 1.

The switch-operating mechanism forming no part of my invention is not shown in detail; but in the drawings 1 represents the vertical rock-shaft, whose rotation for setting 35 the switch also sets the signal-light, whose lens-carrier or lamp-housing is shown in the drawings in position for giving the appropriate signal. Said lens-carrier or lamp-housing is secured to the annular base 3, 40 which has at one side a stem 4 at right angles therewith adapted to be inserted in a socket 5 in the lever-arm 6, which is a casting mounted upon the upper end of said shaft 1 and having said socket 5 offset from the shaft 45 and having protruding upwardly in line with the shaft the stud or post 7, which thus stands up centrally within the annular base 3 of the lamp-housing.

8 8 are conduits for the electric-circuit 50 wires to supply any number of switch-lights

in the yard or system to which the one shown in the drawings may belong. The conduits enter the fuse-box 9, which is located adjacent to the base or switch-stand 10, which supports the switch-operating mechanism including the 55 vertical shaft 1, and from the upper end of said box a conduit 11 extends to nearly the height of the annular base 3 of the lamp-housing and then is deflected horizontally, so as to protrude under said base and be upturned within 60 the same alongside the stud or post 7, which, as stated, is located centrally within said base. A tie-plate 12 is apertured to pass onto the stud 7 and also apertured to pass onto the upturned end of the conduit 11. Said tie- 65 plate has above and below it on the stud 7 elastic cushions formed by coiled springs 13 and 14, the whole assemblage being retained by a cotter-pin 15 above the upper spring. On the upturned end of the conduit 11 the tie- 70 plate 12 is bound between two nuts 16 and 17. Above the upper nut 17 there is secured on said upturned end of the conduit the standard 18 for the incandescent lamp 19, which is suspended from the overhanging upper arm 20 75 of said standard and is thereby held substantially at the intersection of the axes of the several lenses 20^a 20^b 20^c, mounted in the lamp-housing. The foot 21 of the standard 18 is lodged on said upturned end of the conduit 80 11 between two rubber cushions 22 22 and is held by a clamp-nut 22^a, screwed onto the end of the conduit above the upper cushion. The circuit-wires 24 24 for the lamp extend out from the upper end of the conduit and are threaded 85 through an aperture 25 in the standard and passed thence through guide-eyes 26 and 27 and through the insulating-bushing 28 in the upper horizontal arm of the standard to the lamp-socket 19^a, which, with the lamp 19 90 therein, is thereby suspended by means of the wire. The standard is preferably curved outwardly opposite the lamp-bulb to avoid the danger of breaking the lamp from striking the standard in the oscillation of the lamp. 95 The arrangement of the circuit-wires in the switch-box is that which is familiar to electricians and requires no specific description beyond noticing that the main-line wires 30 31 are connected, respectively, to the conducting- 100

plates 32 33, which are insulated from each other on the insulating-base 34, and that from said two plates 32 and 33 the two wires 30^a and 31^a lead to the lamp, thus constituting a 5 branch circuit off from the main circuit. The direct attachment of the wires 30^a and 31^a is made to binding-posts 35 and 36, set in the insulating-base 34, said binding-posts being connected with the binding-screws 37 38 on 10 the plates 32 and 33, respectively, by fuse-wires 39 39.

The lamp-housing is secured in place against unauthorized removal by a padlock 40, engaged through the lower end of the laterally-situated stem 4 of the annular base 3. This stem is slightly tapering and rectangular, the socket 5 being of the same form, so that without necessity for exceptional accuracy in construction, and, indeed, so that the parts may be used 15 without machining, a snug fit and engagement between the stem and its socket is obtained. The annular base is of sufficient interior diameter to permit the housing to be lifted off over and around the lamp and its standard, 20 and for convenience of the attendant it may be supported while changing the lamps or cleansing the lenses by having the laterally-situated stem reinserted in the socket in reverse position—that is, turned around one 25 hundred and eighty degrees from the position at which the housing incloses the lamp—thus avoiding the necessity of laying it on the ground or otherwise exposing it to injury while attending to the lamp and also giving 30 it steadiness of position for cleansing the lenses.

The connection afforded by the tie-plate 12 from the standard or rock-shaft 1 to the conduit-arm 11 gives to the lamp the firm support of said shaft and makes it unnecessary to rely upon the stiffness of the conduit 11 or the firmness of its connection to the fuse-box or other support. This makes it possible to employ for said conduit 11 and its connections 40 much lighter parts than would otherwise be necessary, their only function being to protect the wires and the requirement of strength being that they are not too fragile to be left in said exposed position—that is, they do not 45 necessarily carry any considerable weight except their own. The springs between which the tie-plate is interposed on the post 7 absorb the jar and vibration which would otherwise rapidly destroy the lamps by causing rupture 50 of the carbon filaments, and the same result is prevented in so far as it might be caused by vibration communicated through the conduit 11 by the rubber cushions between which the lamp-standard 18 is bound to the upturned end 55 of the conduit 11, as described.

The construction shown, which comprises the annular base 3, with the laterally-situated arm 4 for attaching it to a support on the switch-stand, is adopted for the purpose of 60 adapting the device to be employed with the

ordinary or common form of lamp-housing made for use with other form of lamp, such lamp-housings being commonly constructed at the upper part, as shown in the lamp-housing in the drawings, having at the lower part 70 a cylindrical neck 41, at which it can be cut off from the lower portion and secured to the annular base 3, as illustrated.

A distinct and important advantage is gained 75 by bringing the conduit-pipes 8 8 upward from their underground course and connecting them with the switch-box 9 above ground, as compared with the customary construction for analogous purposes, which is to lead off from the main circuit-wires in the underground conduit branches into a switch-box. In said customary construction the joint between the main conduit and the branch which must extend upward therefrom to contain the branch wires being necessarily under ground 80 liability to leakage or injury of the joint by frost permitting the access of moisture and danger of short-circuiting is very considerable, and defects necessitating repairs at such points require excavation, and the particular 85 joint at which such attention is necessary can be located only with great difficulty. By the construction herein shown all junctions in the conduit for the purpose of branching are above ground, being, in fact, merely the junctions of 90 the conduits 8 8 with the switch-box. Inspection and repairs are rendered easy and the danger of short-circuiting greatly diminished. 95

I claim—

1. A switch signal-light comprising, in combination with the switch-standard, a lamp-housing mounted thereabove and supported thereon; an electric lamp and a conduit for the circuit-wires thereto extending underneath the lamp-housing; a lamp-standard mounted 105 on the conduit and extending up into the housing for carrying the lamp therein, and a tie-plate fast to the conduit and supported pivotally on the switch-standard.

2. A switch signal-light comprising, in combination with a vertical rotatable switch-standard, a lamp-housing mounted thereabove and supported thereon; an electric lamp and a conduit for the circuit-wires leading thereto extending under the housing; a standard extending up therefrom for carrying the lamp within the housing; a tie-plate rigid with the conduit pivotally connected with the standard about the axis of the latter, and elastic cushions between which the tie-plate is bound at 115 its said pivotal connection.

3. An electric switch-light comprising, in combination with the vertical rotatable switch-standards, a lamp-housing mounted thereabove and supported thereby; an electric lamp in the housing, and a conduit for the circuit-wires leading thereto, extending under the housing; a standard mounted on said conduit for carrying the lamp in the housing; means by which the conduit obtains 125 130

support from the switch-standard, and elastic cushions between which the lamp-standard is bound at its fastening to the conduit.

4. In an electric switch-signal light, in combination with the vertical and rotatable switch-standard, a lever-arm fast upon the upper end thereof, having a non-circular tapering socket offset from the axis, and the lamp-housing having an open annular base provided with a laterally-situated tapering stem to fit the socket, said socket and stem being adapted for fitting the latter into the former in two positions, one, that at which the housing is located above the standard, and the other a position at which it is offset therefrom.

5. A switch signal-light comprising, in combination with a switch-standard, a lamp-housing mounted thereabove and supported thereon; an electric lamp within the housing, and an exterior conduit for circuit-wires leading thereto pivotally supported on the standard.

6. A switch signal-light comprising in combination with a switch-standard, a lamp-housing mounted thereabove and supported thereon; an electric lamp within the housing; a conduit for the circuit-wires leading to the lamp provided with means for supporting the latter, and pivotally supported on the standard.

7. A switch signal-light comprising, in combination with a switch-standard, a lamp-housing mounted thereabove and supported thereon; an electric lamp within the housing; a conduit for the circuit-wires leading to the lamp, provided with means for supporting the lamp, said conduit having pivotal connection with

the standard and elastic cushions interposed between the same and the standard at said pivotal connection.

8. A switch signal-light comprising, in combination with a switch-standard, a lamp-housing mounted thereabove and supported thereon; an electric lamp within the housing; a conduit for the circuit-wires leading to the lamp; a standard for supporting the lamp secured to the conduit and elastic cushions interposed between said conduit and the lamp-standard at the point of fastening of one to the other.

9. In a switch signal-light, a support for the lamp-housing consisting of an annular base adapted to be made fast to said housing, said base having a laterally-situated arm for mounting it on the standard.

10. In a switch signal-light structure, in combination with an electric lamp and the housing and standard for the same, a switch-box mounted in the vicinity of the standard; underground conduits for the inleading and outleading wires, both emerging from the ground and connected above ground with the switch-box; circuit-wires in said conduits, and connections for the same in the switch-box.

In testimony whereof I have hereunto set my hand, in the presence of two witnesses, at Chicago, Illinois, this 23d day of September, A. D. 1903.

JUDSON McFELL.
